UNITED STATES PATENT OFFICE.

THEODORE VIRGIL MORRISON, OF ATLANTA, GEORGIA, ASSIGNOR TO ALPHA LAMBDA TAU FRATERNITY, A CORPORATION OF GEORGIA.

DESIGN FOR A BADGE.

Application filed May 7, 1928. Serial No. 26,599. Term of patent 14 years.

To all whom it may concern:

Be it known that I, THEODORE VIRGIL MORRISON, a citizen of the United States, residing at Atlanta, in the county of Fulton and State of Georgia, have invented a new, original, and ornamental Design for Badges, of which the following is a specification, reference being had to the accompanying drawing, forming part thereof.

I claim:

The ornamental design for a badge, as shown.

In testimony whereof I affix my signature.

THEODORE VIRGIL MORRISON.
